RECORD PLAYER OR SIMILAR ARTICLE

Charles F. Pohlmann, Syracuse, N.Y., assignor to General Electric Company, a corporation of New York

Filed Apr. 30, 1962, Ser. No. 69,890

Term of patent 14 years

(Cl. D56—4)

FIG.1.

FIG.2.

FIG.4.

FIG.5.

FIG.3.

FIG.6.

FIG.7.

FIG. 1 is a perspective view of a record player showing my new design, looking substantially toward the top thereof;

FIG. 2 is a reduced top plan view;

FIG. 3 is a sectional view taken at the line 3—3 of FIG. 2;

FIG. 4 is a reduced front elevational view;

FIG. 5 is a reduced rear elevational view;

FIG. 6 is a reduced right side elevational view; and

FIG. 7 is a reduced left side elevational view.

I claim:

The ornamental design for a record player or similar article, substantially as shown.
